(57) **CLAIM**

The ornamental design for a barbecue grill as shown and described.

DESCRIPTION

FIG. 1 is a perspective view of a barbecue grill showing my new design;
FIG. 2 is another perspective view thereof;
FIG. 3 is a front view thereof;
FIG. 4 is a back view thereof;
FIG. 5 is a left view thereof;
FIG. 6 is a right view thereof;
FIG. 7 is a top plan view thereof;
FIG. 8 is a bottom plan view thereof;
FIG. 9 is a partial enlarged view of portion 9 in FIG. 1; and,
FIG. 10 is a partial enlarged view of portion 10 in FIG. 2. The broken lines depict portions of the barbecue grill and form no part of the claimed design.

1 Claim, 10 Drawing Sheets(56)
